UNITED STATES PATENT OFFICE.

DOMINGO ANGLADA, OF NEW YORK, N. Y., ASSIGNOR TO WOLF SAFETY LAMP CO. OF AMERICA, INC., OF BROOKLYN, NEW YORK, A CORPORATION OF NEW YORK.

ILLUMINATING AND SIGNAL LAMP.

Application filed December 5, 1924. Serial No. 754,055.

This invention relates to an illuminating and signal lamp which is especially used by "track walkers", car inspectors and by workmen in subways, on railroads and in tunnels. 55

Heretofore "track walkers" and workmen engaged along railroad tracks have been greatly handicapped by the type of kerosene lamp in use, which failed to provide sufficient illumination and without any substantial warning signal to make their presence on the track known to an operator of an approaching train. Another disadvantage arising out of the use of the old type 10 of kerosene lamp was its extinguishment by the suction created by a passing train which left the workmen, particularly when engaged in subways and railroad tunnels without means to illuminate their way and without any means to give warning of their presence on the track. Such difficulties, as far as I am aware, have never been overcome and this invention, for the first time, provides a satisfactory means of constantly illuminating the path of the workmen, insuring 15 constant illumination and providing a sufficient and reliable warning of their presence in the path of an approaching train. 20

Other advantages of its construction will appear from the specification and drawings. 30

The figures of the drawings represent respectively:

Fig. 1 a front elevation of this invention; Fig. 2 a side elevation; Fig. 3 a vertical section through the center of Fig. 2; Fig. 4 a vertical section on line 4-4 of Fig. 3; Fig. 5 a horizontal section on line 5-5 of Fig. 3; Fig. 6 a horizontal section on line 6-6 of Fig. 3 as observed from the bottom of the 40 lamp.

The water reservoir 1 is filled with water by removing the cap 2 and the water flows through the aperture 3, in the water tube 4, into the carbide chamber 5. The gas generated by the action of the water on the carbide is filtered by passing through the filter mass 6 and then is burned at the burner 7. The filter mass is retained in place against the underside of the water reservoir 50 1 by the plate 8, which is held against the filter mass by contact of the bent end of the spring 9 against the nipple 10. It is to be noted that the plate 8 is of less diameter than the diameter of the filter mass 6, so that

the acetylene gas may pass through the filter mass around the edge of said plate. The water reservoir and the carbide chamber are secured together by corresponding screw threads in the nipple 10 and the bolt 11, which parts are caused to be engaged by rotating the bolt by means of the wings 12. 60

The burner 7 projects through an opening in the burner housing 13 and the burner housing is secured to the flat side 15 of the water reservoir 1, in spaced relation thereto, by means of the arms 14 suitably secured at their respective ends to the burner housing and to the flat side of the water reservoir. 65

The spacing of the burner housing 13 from the water reservoir 1, provides a ventilating space 24 between the housing and the water reservoir as is particularly observable in Figs. 3 and 5. The walls of the burner housing provide a reflector whereby the illuminating rays from the burner 7 are projected 70 forwardly of the lamp. The front end of the burner housing is provided with a lens 16 and suitable ventilating openings 17 provided at the rear of the lens 16. 75

A "danger signal" 18 is provided at the rear side of the water reservoir and in line with the burning flame so that the presence of the user of the lamp will be signaled to the engineer or motorman controlling the train and which danger signal consists of a 80 suitably mounted lens of ruby or red color. Light from the burner 7 is transmitted to the danger signal 18 through the light channel, which is formed by the tubing 19 passing 85 through the water reservoir 1 and secured 90 by soldering at the places where it passes through the forward and rear walls of the water reservoir 1. A strengthening plate 20 is riveted to the flat side 15 of the water reservoir and around the light tube 19. 95

A suitable handle 21 is secured to the arms 22, fastened on the water reservoir 1 by means of the screws 23. A grip of the handle 21 is lengthwise of the lamp and substantially parallel to the light channel 100 so that, as the user carries it, the illuminating stream of light will be directed forwardly and the danger signal will be directed rearwardly.

No particular importance is placed upon the shape of the light channel, inasmuch as it may be altered at will and may, if desired, be shaped like the burner housing 13 so that

its sides will be flaring, but it is important that the danger signal 18 be in line with the flame so that it is illuminated.

It is to be understood that a lamp of this character produces great candle power and is not readily extinguished. In fact it burns with as much, if not greater, efficiency when exposed to the suction of passing trains as it does in a still atmosphere. The high power acetylene flame illuminates both in a forward and rearward direction and due to the ventilating arrangement the lamp is kept from overheating.

What I claim is:

15. 1. An illuminating and signal lamp comprising a water reservoir, a carbide chamber, a burner, a reflector surrounding the burner, a light channel passing through the water reservoir and water tight with respect thereto, said light channel having one end thereof in proximity to the flame produced at the burner and the other end carrying a danger signal.
20. 2. An illuminating and signal lamp comprising a water reservoir, a carbide chamber, a burner, a reflector adapted to project the illuminating rays from the burner forwardly of the lamp, a danger signal at the rear of the lamp and spaced from the reflector and a ventilating space between the reflector and the danger signal.
25. 3. An illuminating and signal lamp comprising a water reservoir, a carbide chamber, a burner, a housing for the burner, a lens in the forward end of the housing wherfrom illuminating rays are adapted to be projected, a light channel through the water reservoir permitting the projection of light rearwardly of the flame and a danger signal at the rear end of the light channel.
30. 4. An illuminating and signal lamp comprising a water reservoir, a carbide chamber, a burner, a housing for the burner, a lens in the forward end of the housing wherfrom illuminating rays are adapted to be projected, an elongated light channel through the water reservoir permitting the

projection of light rearwardly of the flame, an enlargement at the rear end of the channel and a danger signal supported by said enlargement.

5. An illuminating and signal lamp comprising a water reservoir, a carbide chamber, a burner, a reflector adapted to project the illuminating rays produced at the burner forwardly of the lamp, said reflector being spaced from said water reservoir to permit the circulation of air between the water reservoir and the reflector, a danger signal at the rear of the water reservoir and a light passage from said reflector to said danger signal permitting the light produced at said burner to illuminate the danger signal by the passage of light through said light passage.

6. An illuminating and signal lamp comprising a water reservoir, a carbide chamber, a burner adapted to burn acetylene in the carbide chamber, a housing for the burner, said housing comprising a reflector and a lens at the forward end of the reflector, a danger signal in line with the flame adapted to burn at said burner and spaced from said burner a greater distance than the spacing of the forward lens from said burner and a water reservoir between said danger signal and said burner.

7. A portable illuminating and signal lamp comprising a water reservoir, a carbide chamber, a burner connected to said carbide chamber to form a source of light, a reflector for said source of light positioned adjacent said reservoir, a lens in said reflector, said reflector being provided at its rear end with an aperture, an elongated light channel having one end thereof in line with the said aperture and extending to the rear of said reservoir, a colored lens at the rear end of said light channel, said light channel having its axis in alignment with said source of light for conducting light to said colored lens to form a danger signal.

In testimony whereof I have hereunto set my hand.

DOMINGO ANGLADA.
